UNITED STATES PATENT OFFICE.

JAMES J. BIBBY, OF PHILADELPHIA, PENNSYLVANIA, ASSIGNOR OF ONE-HALF TO
DANIEL SNYDER, OF PHILADELPHIA, PENNSYLVANIA.

FLIER SPINNING DEVICE.

1,168,927.

Specification of Letters Patent.

Patented Jan. 18, 1916.

Application filed October 1, 1913. Serial No. 792,745.

To all whom it may concern:

Be it known that I, JAMES J. BIBBY, a citizen of the United States, residing in Philadelphia, Pennsylvania, have invented 5 certain Improvements in Flier Spinning Devices, of which the following is a specification.

My invention consists of a device of the flier type for spinning an untwisted roving 10 into a twisted yarn or thread or for twisting together two or more strands of thread or yarn. Hereinafter for convenience, and to avoid repetitions, I will refer to the device as a spinning machine for producing a 15 twisted thread from an untwisted roving.

One object of my invention is to so guide the roving in its travel over the flier as to prevent it from being thrown outwardly from the flier by centrifugal force or from 20 being disarranged by air pressure upon it as it is rapidly carried around with the flier.

A further object of my invention is to prevent displacement of the flier from its 25 proper plane of rotation and to effect such rotation with a minimum of friction, and a still further object is to insure the winding of the thread in a firm mass or body upon the spool or bobbin.

These objects I attain in the manner hereinafter set forth, reference being had to the accompanying drawing, in which—

Figure 1 is a vertical sectional view of a flier spinning device constructed in accordance with my invention; Fig. 2 is a horizontal section on the line *a—a*, Fig. 1; Fig. 3 is a horizontal section on the line *b—b*, Fig. 1, and Fig. 4 is a side elevation of the bearing stud for the lower end of the flier.

In the drawing, 1 represents part of a projecting arm or bracket which carries the upper bearing for the flier, 2 part of the fixed rail which carries the stud constituting the lower bearing for said flier, and 3 part 45 of the vertically reciprocated builder rail which carries the non-rotating spindle 4 upon which the spool or bobbin 5 (hereinafter for convenience referred to as a “spool”) is mounted.

The flier consists of opposite arms 6 connected at the top by a bridge piece 7 to which is secured a conical block 8 free to turn in a lubricating block 9 secured to the upper bearing so as to render un-

necessary the application of oil to said top 55 bearing of the flier.

The opposite arms of the flier are preferably connected at their lower ends, as by segments 10, so that this portion of the flier constitutes a cylindrical shell, and they may 60 also be connected at an intermediate point, as by segments 11, so as to impart to the flier a degree of rigidity which will prevent distortion or displacement of either of the arms of the same. Each of the arms 65 of the flier has, on its outer face, a projecting rib 12 in which is formed a groove 13 (Fig. 2) said grooves 13 of the arms being in line with slots 14 formed in the conical top of the flier so that the roving 70 supplied to the flier through the central eye 15 in the upper arm 1 will be confined in its passage from said eye to the delivery eye 16 of the flier and will be prevented by the outer flange of the rib 12 from being displaced radially by reason of centrifugal 75 force while the radial web of said rib 12 will protect it from displacement which might otherwise be caused by the action of the air upon it as it is rapidly rotated with 80 the flier arm.

The stud 17 is tubular and has an annular flange 18 and a depending tubular stem 19, the flange resting upon the top of the fixed rail 2 and the stem passing through an 85 opening in said rail and being threaded at its lower end for the reception of a nut 20, the latter bearing upon the under face of the rail and serving to secure the stud 17 thereto. The flier has, at its lower end, a depending tubular sleeve 21 adapted for the reception of a belt whereby it can be rotated, said sleeve having projecting flanges 22 and 23 which serve to retain the belt in its proper position on the sleeve, the lower 95 flange 23 having in its under face an annular groove forming a race for a series of balls 24 which run in a similar race formed by an annular groove in the upper face of the flange 18 of the bearing stud 17. This 100 ball bearing at the lower end of the flier and the bearing block 9 at the upper end of the flier serve to retain said flier in its proper vertical position and they have their axes in the same vertical plane so as to insure 105 the rotation of the flier upon a central vertical axis concentric with that of the non-rotating spindle 4 which has, at its lower

end, a step or button 25 resting upon a correspondingly formed seat in the vertically reciprocating builder rail 3.

The spindle 4 has a conical upper end 5 which is adapted to a seat at the upper end of a tubular sleeve 26, the latter surrounding the upper portion of the spindle and having, at its lower end, a flange 27 upon which is mounted a friction ring 28 of leather, felt, or like material, for contact with the bottom face of the flange at the lower end of the spool 5. The bearing stud 17 has formed in its outer face a spiral groove 29 so that oil, introduced at the top 10 of the stud through the opening 30 in the depending sleeve 21 of the flier, is distributed through the surface of the stud, properly lubricates the bearing provided thereby, and finally gains access to and 15 lubricates the ball bearing 24 interposed between the flange 23 of the sleeve 21 and the flange 18 on the stud.

The roving passes first through the eye 15 in the arm 1, thence down through one 20 of the slots 14 in the conical cap 8 of the flier, and thence, through the groove 13 in the rib 12 on one of the arms 6, to the delivery eye 16, from whence it passes to the spool 5 and is wound thereon. As the flier 25 rotates in the direction of the arrow, Fig. 2, the spool is caused to rotate therewith by reason of the pull of the thread as it is wound upon the spool, but a firm, close winding of the thread upon the spool is insured by reason of the braking effect of the friction ring 28 and of a similar friction 30

ring 31 interposed between the base flange 27 of the sleeve 26 and a flange at the top 40 of a sleeve 32 which surrounds the spindle 4, extends down through the stud 17 and its stem 19, and is, at a point below the rail 2, acted upon by a weighted lever 33, whereby its upper flange may be caused to press upwardly against the washer 31 with any desired degree of force less than that 45 necessary to lift the weight of the sleeve 26 plus that of the spool and its load, so as to regulate the degree of frictional retardation exerted upon the sleeve 26, and thence upon the spool 5.

The guide rib 12 may, if desired, be formed upon only one of the flier arms 6 but it is preferable to form such rib upon both of the arms in order that the flier may be properly balanced.

I claim:

The combination, in a flier spinning device, of a rotatable flier, a non-rotating spindle, a sleeve rotatable on said spindle, a spool carried by said sleeve, a friction device acting upon said sleeve, another sleeve carrying said friction device, and a lever with adjustable weight for imparting a variable amount of lifting force to said second sleeve.

In testimony whereof, I have signed my name to this specification, in the presence of two subscribing witnesses.

JAMES J. BIBBY.
